Mitchell & Sawyer.

UNITED STATES PATENT OFFICE.

EDSON B. WILCOX, OF MERIDEN, CONNECTICUT.

ELECTRIC CONNECTOR.

1,201,783.

Specification of Letters Patent. Patented Oct. 17, 1916.

Application filed October 14, 1915. Serial No. 55,836.

To all whom it may concern:

Be it known that I, EDSON B. WILCOX, a citizen of the United States of America, residing at Meriden, Connecticut, have invented 5 a new and useful Electric Connector, of which the following is a specification.

The general objects of this invention are to provide a simple and efficient form of 10 plug connector which can be used interchangeably in different types of sockets, my invention aiming particularly to provide such a connector which can be used in sockets of either the two wire "all insulated" or the one wire "grounded" systems of 15 electrical distribution.

In prior applications of mine, I have disclosed and claimed interchangeable plug 20 constructions having end contacts for engagement with the contacts of a two wire socket and having a center contact connected with one of the end contacts and a side contact connected with the other one of the 25 end contacts for use when the plug is inserted in a one wire socket.

To avoid a ground, when the plug is used 30 in a two wire socket and the side contact is not necessary, the connection between the end contact and the side contact was made severable or detachable so that the side contact could be disconnected from the circuit 35 when the plug was to be used in the two wire all insulated type of socket.

A special object of my present invention 40 is to automatically disconnect this grounded side contact from the circuit when the plug is used in a two wire socket, and to automatically connect the side contact in circuit when the plug is used in a one wire type of socket.

These objects I have accomplished in the 45 form of my invention herein disclosed, by utilizing the center contact, which is present in sockets of the one wire type, as a means for coupling the side contact in circuit, the plug being so constructed that normally the side contact will be out of circuit. As a result of this the only time that the side contact is in circuit is when it is needed, that is, when the plug is used in a one wire 50 type of socket.

Details of the structure and other features

of the invention will appear as the specification proceeds.

The accompanying drawing illustrates the 55 invention embodied in a practical and preferred form, it being understood however that changes and modifications may be made without departing from the real spirit and scope of the invention.

In the drawing:—Figure 1, is a perspective view of the invention as embodied in the form of a lamp and showing it ready for insertion in a socket constructed to receive it. Fig. 2, is a longitudinal sectional view illustrating the use of the invention in 65 a socket of a two wire all insulated type. Fig. 3, is a similar view illustrating the use of the invention in a socket of the one wire or grounded type. Fig. 4, is a detail perspective view illustrating the construction 70 and arrangement of the contacts.

In the particular embodiment of the invention herein disclosed, the plug is shown in the form of a lamp base, the body of which is made up of a shell or sleeve 7, this 75 sleeve being made of metal and constituting the side contact of the plug. On the end of the plug are mounted the end contacts 8 and 9, these contacts constituting in this particular instance the terminals of the filament 10, this filament being connected to said contact by feed wires 11 and 12. Also mounted on the end of the plug is a center contact 15 which comes into use when the plug is used in a socket of the one wire type. 85 This center contact is connected with one of the end contacts, in the illustration with the contact 9, it being shown as in the form of an integral inwardly extending extension of said end contact.

The side contact is automatically connected in circuit when the plug is used in a 90 socket of the one wire type by means of a grounding contact 17 normally supported out of engagement with the end flange 18 of 95 the shell 7 and adapted to be forced by the pressure of the center contact of the one wire socket into contact with said flange. In the illustration this grounding contact is in the form of a spring extension of the end contact 8 extended across the end flange of 100 the shell 7 and normally supported out of

engagement therewith by the layer of insulating material 19, said insulating material having an opening at the center designated 20 to permit of the spring contact 17 being 5 forced into engagement with the flange.

In the illustration the pressure for forcing the grounding contact into electrical connection with the side contact is transmitted from the center contact of the socket 10 through the medium of the center contact 15 of the plug and an insulating block 21 interposed between said center contact 15 and the grounding contact 17.

The several contacts are preferably 15 mounted on an insulating base 22 carried by the end of the plug and the insulating layer 19 which normally supports the spring contact out of engagement with the end flange of the shell may be made as a part of 20 this insulating base. This base may be secured to the end flange of the shell by fastenings such as screws 23.

In Fig. 1 I have illustrated a socket 27 of the bayonet slot type much used in automobile lighting systems and have shown the 25 plug provided with a pin 25 for interlocking engagement in the bayonet slot 26 in the socket.

The use of the invention will be clear from 30 Figs. 2 and 3. In Fig. 2 the plug is shown engaged in a socket 30 of the two wire all insulated type having contacts 31 and 32 making engagement with the two end contacts 8 and 9 on the plug. In this case the 35 flow of current is simply from the socket contacts, which are disposed on opposite sides of the center line of the socket to accord with the similar disposition of the plug end contacts and by way of said end contacts and lead wires 11 and 12 through the filament. The spring contact 17 being in this case disengaged or disconnected from the side contact, there is no grounding of the circuit at any point.

In Fig. 3 the plug is shown used with a 45 socket of the one wire or grounded type, the body 35 of this socket being connected at 36 with the grounded side of the line. The metallic shell 7 of the plug, contacting with 50 the socket body 35, constitutes in this case the side contact of the plug. The other contact of the socket is provided by the centrally disposed contact member 37. This central contact engages the center contact 15 55 of the plug, thereby establishing electrical connection for one side of the filament, by way of said center contact 15, end contact 9 and feed wire 12 and at the same time serves by its pressure, transmitted through the insulating block 21 to carry the spring extension 17 of the other end contact 8 into electrical connection with the end flange of the side contact. When the spring contact 17 is thus forced into electrical connection with

the side contact, the return of the current 65 through the grounded side of the line is provided for by reason of the engagement of the side contact with the grounded socket body.

What I claim is:

1. In a plug and socket connection, a plug 70 body, end contacts carried by said plug body, a center contact on said plug body connected with one of said end contacts, a side contact on said plug body and means operable upon the insertion of the plug in a socket for automatically connecting one of the end contacts 75 with said side contact.

2. In a plug and socket connection, a plug 80 body, end contacts carried by said plug body, on opposite sides of the center thereof, a center contact connected with one of said end contacts, a side contact carried by the plug and a spring contact connected with one of the end contacts and adapted to be forced by the center contact into electrical connection 85 with the side contact.

3. In a plug and socket connection, a plug 90 body, end contacts carried by said plug body and disposed on opposite sides of the center thereof, a center contact connected with one of said end contacts, a side contact having a flange extended beneath the center contact, a spring contact connected with one of the end contacts and extended beneath the center contact and an insulating block 95 interposed between the center contact and said spring contact adapted upon pressure on the center contact to force said spring contact into engagement with the flange of the side contact.

4. In a plug and socket connection, a plug 100 body, two end contacts carried by said plug body and disposed on opposite sides of the center thereof, a center contact connected with one end contact, a side contact on the 105 plug body having an end flange extended beneath the center contact, and a contact electrically connected with the other one of the end contacts and extended beneath but insulated from the center contact to be thereby 110 forced by said center contact into electrical engagement with the end flange of the side contact.

5. In a plug connector, a metal shell having an end flange, an insulating base carried 115 by said end flange, two end contacts carried by said insulating base on opposite sides of the center thereof, a center contact connected with one of said end contacts, a spring contact connected with the other one of the end contacts and extended between the end flange of the shell and the center contact and an insulating connecting block between the center contact and the spring contact.

6. A lamp base, two end contacts disposed 125 on opposite sides of said lamp base, a center contact connected with one of said end contacts, a side contact and means operated by

the center contact for electrically connecting the other one of the end contacts with said side contact.

7. In a plug and socket connection, a plug body, end contacts carried by said plug body, a center contact on said plug body connected with one of said end contacts, a

side contact on said plug body and a spring contact connected with the other end contact and adapted to be automatically forced into 10 electrical engagement with the side contact upon the insertion of the plug in a socket intended therefor.

EDSON B. WILCOX.
